UNITED STATES PATENT OFFICE.

CLEM J. SCHWIETERMAN, OF NEW YORK, N. Y., ASSIGNOR TO SURRUG CHOCOLATE CORPORATION, OF NEW YORK, N. Y., A CORPORATION OF NEW YORK.

COIN-OPERATED VENDING-MACHINE.

1,213,548.

Specification of Letters Patent. Patented Jan. 23, 1917.

Application filed January 25, 1916. Serial No. 74,073.

To all whom it may concern:

Be it known that I, CLEM J. SCHWIETERMAN, a citizen of the United States, and resident of the city, county, and State of New York, and whose post-office address is 781 East One Hundred and Forty-second street, care of Nelson Tool Company, in said city, have invented certain new and useful Improvements in Coin-Operated Vending-
10 Machines, of which the following is a specification.

My invention relates to machines for dispensing candy, confections, chocolate and the like, and its object is to cheapen the cost 15 of construction and simplify the arrangement and combination of parts, and particularly to dispense with the use of the manual act of discharging the article to be vended, following the release by the detaining devices of the coin. With these objects in view, I have devised the construction shown and described in the drawings forming part hereof, and specifically pointed out in the claims appended hereto.

25 In the drawings forming part of this specification, Figure 1 is a transverse sectional elevation through the machine substantially on the line *a—a* of Fig. 2; Fig. 2 is a sectional elevation substantially on the line *b—b* of Fig. 1; Fig. 3 is a front elevation of a portion of the case showing the method of pivoting the trap plate thereto; and Figs. 4, 5 and 6 are respectively sectional elevations from a portion of the casing showing the positions occupied by the trap plate and tripping mechanism, during the three stages of the operations through which these parts go.

Similar reference characters indicate corresponding parts throughout the several views.

In order to properly house the devices hereinafter described, any convenient or desirable form of casing may be used. The one illustrated here consists of a back plate 1, having a dependent bracket 2, apertured at the ends, as at 3, to allow the article to be vended to be dropped therein and removed laterally therefrom. At 4 is a front plate 0 supported at the bottom by a ledge 5 extending from the bracket 2, and provided with a top 6, abutting against the back 1 to which it may be secured by a lock, or otherwise, as desired.

The back plate 1 has sides 7 which serve, 55 with the other parts, to inclose the operating mechanism. At 8 is a plate conveniently secured within the casing as by a flange 9 secured to the ledge 5 of the bracket 2, at the bottom, and otherwise secured to the sides 7 60 of the casing. This plate and the back 1 form a containing chute, its lower opening alining with the depression in the bracket 2. One of the side plates 7 is apertured, as at 10, for the insertion of a coin. This aperture leads to a coin chute 11, the inner wall of which is secured to the sides 7 of the casing and which has an inwardly and downwardly curved mouth 12. This chute is located in the space 13 between the plates 4 70 and 8, the bottom being closed by the flange 9 and ledge 5 respectively, so as to make a container for the coins passing from the chute 11, access to which is had only by removal of the plate 4. The merchandise 75 chute 14 is located on the opposite side of the plate 8.

My improvements have been specifically designed for the purpose of dispensing articles contained in a cylindrical body, such as shown at 15, and which have a diameter substantially coextensive with the distance between the sides 7 of the casing; although it will be clear that my improvements may be used in connection with a differently constructed casing and for the purpose of dispensing articles of entirely different and varying shapes.

An important feature of my invention consists in means, contained within the merchandise chute, which will support the article to be vended combined with further means for tripping or otherwise moving the said support so as to free the article and allow it to pass down the chute and be vended, 90 such means automatically returning to the first position where it will support the next succeeding article and prevent it from passing the support until it is again freed by the action of the coin operated devices.

100 The specific embodiment of means which I have employed in the structure disclosed herein for accomplishing these results will now be described.

In the walls 7 of the casing, or in any 105 other desirable way, is pivoted, as at 16, a segmental plate 18 with its concave surface presented to or facing the chute 14, and

which is preferably pivoted so close to the plate 8 that it will, at the end of its two pivoting actions, hug the plate 8 as close as possible, in order to avoid choking the passage. Directly opposite the plate 18, which 5 from the nature of its action I call a trap plate, the wall 1 is provided with a segmental groove 19 for a purpose hereinafter described. The wall 8 immediately at the rear of the plate 18 is provided with a slot 20 and through this slot projects a pin 21 secured at one end to the back of the trap plate.

At 22 is a gravity latch or detent pivoted 10 to the plate 8 by the pin 23. One end of the latch is provided with a downwardly and forwardly extending nose or projection 24 which has a plane of movement within the opening or mouth of the chute 11, and the 15 other end of the latch is provided with a weighted enlargement or counter poise 25. The nose or projection 24 is slotted, as at 26, and through this slot the pin 21 extends.

The operation of the device as thus constructed is as follows: Normally the counter poise weight 25 maintains the nose or projection 24 in operative alignment with the chute 11. As the coin is dropped into the chute, it passes through the curved portion 12 and contacts with the nose or projection 24, the weight of the nose and the coin combined being greater than that of the counter poise 25, and the resistance to vibration which is imposed upon the trap 20 plate 18, the latch 22 will be vibrated upon its pivot 23; a ledge 27 being added as a continuation of the chute 11 in order to continue the descent of the coin 28 in operative contact with the nose 24 until the 30 same is swung into the position shown in dotted lines in Fig. 1, when the coin will be freed from the contact with the nose and drop to the bottom of the space 13.

The articles 15, previous to the insertion 40 of the coin, have been lying in the chute 14, one superposed upon the other, the lowermost one bearing on the upper edge of the trap plate 18, as shown in Fig. 2. The trap plate being pivoted and connected with the latch 50 22, by the pin 21 and slot 26, as hereinbefore described, will be vibrated by the downward movement of the latch 22, allowing the lowermost article 15 to pass in front of it and move into the recess formed by the 55 projection 19 in the plate 1.

The counter poise 25 restores the latch 22 to its normal position, shown in Fig. 6, which movement restores the trap plate 18 to the position shown in that figure, with 60 the upper edge of the trap plate engaging the next article; the lowermost article having passed down the chute. This operation, while it has freed the lowermost article 15, which has previously rested upon the trap 65 plate, causes the chute 14 to be narrowed,

so that the succeeding article has come to rest upon the upper edge of the trap plate 18, where it will be supported until the latch is again energized in the manner heretofore set forth.

The counter poise 25 acts to restore the latch to its normal position of confronting the mouth of the chute 11, but the slot and pin connection between it and the trap plate is such as to allow the weight of the article 70 15 passing over the segmental surface of the trap plate, to vibrate the latter independently of the counter poise 25, so that the weight of such article itself aids and assists the counter poise, and to a certain 75 extent acts independently thereof, in and to restoring the trap plate to its normal position and supporting the article 15 thereon, and the latch in its normal position with relation to the chute 11. Thus it will be 80 seen that the operation of the device is continuously automatic, and rendered certain, whether the weight of the superposed article 85 15 resting on the trap plate 18 be always the same, or be continuously lessened during the 90 operation of the device.

It is manifest that my invention is susceptible to various modifications without departing from its spirit, for I do not intend that it shall be limited to the precise 95 construction shown herein, as the same is broad enough to extend to any embodiment thereof apprehended within the scope of the appended claims.

What I claim is:

1. In a device of the class described, the combination with a suitable casing, of an article chute, a movable trap or support in the article chute, a coin chute, a pivoted latch, a counter poise on one end of said latch, the other end of said latch being disposed in the path of a coin passing through the coin chute, said latch being engaged with the trap plate intermediate the ends of the latch for vibrating the trap plate.

2. In a device of the class described, the combination with a suitable casing, of an article chute, a movable trap or support pivotally mounted in the article chute, a pivoted latch with its pivot at right angles to the pivot of the trap plate, being pivotally engaged with the trap plate between the ends of said latch, one end of said latch adapted to be engaged by a coin passing through the coin chute and means on the other end of said latch for restoring it to its normal position with its coin-engaging end in the pathway of the coin chute.

3. In a device of the class described, the combination with a suitable casing, a coin chute and an article chute, a plate separating said chutes, a trap plate movably mounted in the article chute, and having a projection extending through an opening in the plate, a pivoted latch mounted on the

plate and having an opening intermediate its ends engaging the projection on the trap plate and for vibrating said plate.

4. In a device of the class described, the combination with a suitable casing, of an article chute and a coin chute disposed within said casing and separated by a plate, a trap plate having a surface configuration adapted to engage the article to be vended 10 pivoted to the walls of the casing, a projection on said trap plate extending through an aperture in the plate separating the coin chute and article chute, a latch pivoted to said plate having a portion disposed in the 15 path of the coin chute and adapted to be engaged by a coin passing through said chute, a counterpoise on the latch and an opening in said latch engaged by the projection on the trap plate.
- 20 5. In a device of the class described, the combination with a suitable casing, of an article chute and a coin chute disposed within said casing and separated by a plate, an annular trap plate pivoted to the side walls 25 of the casing, a projection on the rear of said trap plate extending through an opening in the plate between the chutes, a latch pivoted to said plate having one of its ends disposed in the path of the coin chute and 30 adapted to be engaged by a coin passing
- through said chute, a counter poise on the other end of said latch, an opening in said latch engaging the projection on the trap plate for vibrating said trap plate and a segmental groove formed in the rear wall of 35 the casing opposite the trap plate.
6. In a device of the class described, the combination with a suitable casing, of an article chute and a coin chute disposed within said casing and separated by a plate, a 40 trap plate having a surface configuration adapted to engage an article to be vended pivotally secured to the side walls of the casing, a projection on the rear side of the trap plate extending through an opening in 45 the plate separating the coin chute and the article chute, a latch pivotally secured to said plate having its nose disposed in the path of the coin chute and adapted to be engaged by a coin passing through said chute, 50 a counter poise or weight on said latch, an opening in the nose portion of said latch engaging the projection on the trap plate and vibrating said trap plate and a segmental groove formed in the rear wall of the casing 55 opposite the trap plate.

Signed at the city, county and State of New York, this 22d day of January, 1916.

CLEM J. SCHWIETERMAN.
